UNITED STATES PATENT OFFICE.

ALBERT P. BROOMEML, OF YORK, PENNSYLVANIA.

STEAM HEATING APPARATUS.

SPECIFICATION forming part of Letters Patent No. 650,778, dated May 29, 1900.

Application filed February 5, 1900. Serial No. 4,046. (No model.)

To all whom it may concern:

Be it known that I, ALBERT P. BROOMEML, of York, in the county of York and State of Pennsylvania, have invented a new and useful Improvement in Steam Heating Apparatus, of which the following is a specification.

My invention is an improvement in steam heating apparatus having for an object to provide, first, a steam-heating system by which it is possible to regulate the amount of steam admitted to each radiator and to heat each radiator all or part of the way over, as required; second, a system in which all radiators are open to the atmosphere, the heating being accomplished by the circulation of steam without pressure through the radiators; third, a system in which no air-valves are required on the radiators; fourth, a system in which it is impossible for water to accumulate in the radiators; fifth, a system that will work absolutely noiseless; sixth, a system that can be installed with the use of much smaller pipes than ordinarily used, and, seventh, a system in which are provided means whereby the production of steam in excess of the demand will control the damper of the boiler-furnace and will further automatically operate relief devices, whereby the water of condensation will be returned to the boiler, whereby the shutting off of steam from the radiators will automatically open a vent from such radiators to the atmosphere.

The invention consists in certain novel constructions and combinations of parts, as will be hereinafter described and claimed.

In the drawings, Figure 1 is a sectional elevation of a building presenting in somewhat diagrammatic form a heating apparatus embodying my improvements. Fig. 2 is an elevation of the boiler and parts directly associated therewith. Fig. 3 is a side view, partly broken away in section, of a receiver provided with my improvements. Fig. 4 is a cross-section on about line 4-4 of Fig. 3, and Fig. 5 is an end view of the radiator feed-valve. Fig. 6 is a vertical longitudinal section. Fig. 7 is a top plan view, and Fig. 8 a horizontal section, of the radiator-valve.

The boiler A may be of any suitable form of steam-heating boiler, preferably one having a low water-line. The steam supply pipe or feed pipe B is connected ordinarily at the

usual point of outlet of the boiler and is extended in suitable directions and connected by branch pipes C with the heating-radiators D, connecting with such radiator, preferably, but not necessarily, at the top thereof. The feed-pipes connect with the radiators through the medium of the valves E. (Shown in Fig. 1 and in detail in Figs. 5 to 8, inclusive.) 55 This valve E is designed to admit any desired amount of steam to the radiator and will be more fully described hereinafter.

The return-pipes F lead from the radiator back to what I term the "receiver" G. The receiver G is shown in detail in Figs. 3 and 4, and in practice is arranged above the water-line of the boiler and preferably above the steam-space thereof. As shown in Figs. 1 and 2, I form the receiver preferably with 65 glass sides G', so its interior is exposed to view, and it is connected by a pipe G² with the boiler below the water-line of the latter and is supplied with a gage G³ to indicate by the height of water the pressure in the boiler, 70 graduations being provided on the pipe G² or otherwise to indicate the degree of pressure of steam by the height of water in the said pipe.

At its top the receiver G is provided with 75 openings F' for the return-pipes F and with an opening H' for the waste-pipe H, leading to the condensing-radiator I. The bottom of the receiver is tapped for the connection of the pipe G² and also to receive the relief-pipe J, which opens into the steam-space of 80 the boiler. The pipe J is extended within the receiver and has its upper or discharge end arranged above the normal water-line in the receiver. This pipe J is controlled by the safety or relief valve K, provided with 85 and arranged for operation by the float K', which float is arranged in the receiver G and for operation by any excessive rise of water in said receiver.

The float L operates in the receiver G and 90 is carried on an arm or lever L' on a shaft L², carried through a stuffing-box L³, and having an arm L⁴, connected by chain L⁵ with a damper M, which regulates the fire in the steam-boiler furnace. When the water rises in the 95 receiver G, it will lift the float L, which movement of the float closes the damper to a degree relative to the height to which the float L may rise, the damper moving gradually

toward closed position until it is entirely shut. If the water continues to rise in the receiver after the damper M is shut, the relief-valve will be opened by the rise of its float 5 and the pressure in the boiler will be relieved in the manner more fully described herein-after.

The condensing-radiators I, of which there may be any desired number, are connected 10 by a pipe H with the receiver and by a pipe II' with a condensing head or drum I', placed in the attic or above the roof or otherwise suitably located.

The boiler has a glass gage A' to indicate 15 the height of the water within it.

When no steam-pressure is on the boiler, the water in the glass gage A' on the boiler and in the glass gage G³, attached to the receiver G, will stand at the same level. After 20 fire is made in the boiler and steam generated and before any appreciable pressure is produced the steam will pass out through the main supply-pipe and will be discharged into the radiators in such quantities as the 25 valves E will permit. After the radiators are heated from end to end should there be any steam escaping back through the return-pipes F this steam will be discharged into the receiver, and from this receiver the 30 surplus steam thus discharged will pass into the condensing-radiator, where it will be condensed into water and returned to the receiver, from which point it will, of course, return to the boiler. If there is sufficient 35 fire in the boiler to produce a pressure, it will naturally prevent the water of condensation from returning to the boiler until this water has accumulated in the pipe leading from the receiver to the boiler to a sufficient height to 40 overcome the equilibrium, when it will flow into the boiler by gravity.

In the event of sufficient pressure accumulating in the boiler to lift the water into the body of the receiver the water will come in 45 contact with float L and will lift this float, and as soon as the float L is moved upward the damper M will begin to close, which movement will continue until the damper is entirely shut. If steam continues to increase 50 in pressure after the damper is shut, the water will continue to rise in the receiver G until it reaches the float K', attached to the relief-valve K, and will lift the relief-valve from its seat, discharging steam from the steam-space in the boiler into the receiver, from 55 which point it will pass through the pipe II on top of the receiver G into the condensing-radiator I above. In the event of the condensing-radiator not having sufficient surface 60 to condense all the steam that may discharge into it from the relief-valve the surplus steam will pass up the pipe II', connected to the top of the condensing-radiator, and into the condensing-head I', the surface in which condensing-head will be ample to condense all steam 65 that may reach that point.

The valve E is so constructed as to admit

steam to any desired degree to the radiator and to open a vent to the atmosphere when it is adjusted to entirely cut off steam from the radiator. By this valve any desired quantity of steam can be admitted to the radiator, heating the radiator to such a degree as may be necessary to warm the room in which it is placed and making it possible to regulate the 70 temperature of the room to any desired point. As the radiators are open to the atmosphere through the return-pipes and the condensing-radiator, they do not require any air-valves, and the radiators also being open to the atmosphere makes it possible to circulate steam 75 through them without any pressure on the boiler, and there will be no possibility of water accumulating in the radiators. The construction of the valves E is best shown in Figs. 85 5 to 8, inclusive. The valve includes the casing, having a head E', provided with a series of sockets E² for the stop-pin and an opening E³ for the valve-stem, the seat E⁴ having feed-ports 1, 2, 3, and 4 for the steam and an 80 air-port 5 for communication with the atmosphere, nipples 6 and 7 for connection respectively with the steam-feed pipe and with the radiator, the valve proper, N, having a non-circular socket O' for the stem O, and the stem 85 O and its spring and handle devices. The valve N fits on the seat E⁴ and is provided with the series of ports N' N² N³ N⁴, which may be turned to register, respectively, with ports 1, 2, 3, and 4 when the valve is fully 90 opened or to open any desired ones of the said ports 1, 2, 3, and 4 to any desired degree. When the valve is in the position shown in Fig. 8, the steam-ports 1, 2, 3, and 4 are closed and the port N' is in full register with the 95 port 5, opening communication with the atmosphere, breaking the vacuum, and preventing a suction of water from the return-pipe. This is the position of the valve shown 100 in Figs. 6 and 8. If now the valve be moved one point to the right, the port N¹ will register with and open the feed-port 1, the air-port 5 will be closed, and steam will be fed through the port 1 to the radiator. Another step of the valve will open ports 1 and 2, and so on, 105 until the full head of steam is admitted.

The stem O fits at its lower end in the socket O' and extends upward through an opening O² in the head-plate E', being provided beneath said plate with a packing portion or shoulder O³ and with a spring O', bearing between the same and the valve-plate and operating to press the valve to its seat and the portion O³ tightly up against the head-plate E'. On the stem above the head-plate I secure the arm P, having near its outer end the handle P', which has a limited longitudinal movement in the arm and has the stop-pin P², which can be set into any one of the sockets E² to hold the valve in any desired adjustment. The outer end of the arm P is socketed and receives a screw P³, by which the handle can be locked in any one of the sockets E², and a cross-pin P⁴ limits the upward 110 115 120 125 130 135

movement of the handle and prevents its being pulled out of the arm P. The operation of the valve will be readily understood from the foregoing.

5 My system permits the use of much smaller supply and return pipes than those ordinarily employed.

In the event of the fire being neglected and too much steam - pressure being produced 10 there is no possibility of low water in the boiler, since even if the safety-valve should blow for a long while the water will all be condensed in the condensing-radiator and condensing-head and will return to the boiler by 15 gravity, keeping the proper water-supply in the boiler at all times.

The valve illustrated in Figs. 5, 6, 7, and 8 forms the subject-matter of a separate application for patent, Serial No. 9,275, filed in the 20 United States Patent Office March 19, 1900.

Having thus described my invention, what I claim as new, and desire to secure by Letters Patent, is—

1. In a heating apparatus the combination 25 of the boiler, the steam and return pipes, a receiver receiving the discharge of the return-pipes and located above the water-line of the boiler, a connecting-pipe forming an unobstructed passage between said receiver and 30 the boiler below the water-line in the latter, a steam connection between said receiver and the boiler, a valve controlling such connection, and a float in the receiver for controlling said valve.

35 2. In a heating apparatus the combination of the boiler, the steam and return pipes, a receiver above the water-line of the boiler and connected with the boiler below its water-line, damper devices, a float in the receiver for operating said damper, a steam connection between the receiver and the boiler, a valve for controlling said steam connection and a float in the receiver for operating said valve.

3. In a heating apparatus the combination 45 with the boiler and damper of a receiver for the water of condensation, the return-pipes for discharging such water to said receiver, connections between said receiver and the boiler, a float in the receiver, devices whereby 50 the said float may operate the damper, a steam connection between the boiler and receiver and means in the receiver for operation by the water therein, whereby to control such steam connection.

55 4. The combination of the boiler, the damper, the steam-circulating pipes, leading from the boiler, the receiver, the return-pipes leading to the receiver, a pipe connection between the receiver and the boiler below the water- 60 line of the latter, the steam-pipe connecting the steam-space of the boiler with the receiver

and extending upward within such receiver, the valve and its float within the receiver for controlling such connecting steam-pipe, and the float in the receiver and connected with 65 the damper by which to operate such damper.

5. A heating apparatus having a boiler, a receiver for the returned water of condensation, a steam-pipe connecting said receiver with the steam-space of the boiler, a float-operated valve controlling the said steam-pipe 70 and an unobstructed water connection between the receiver and the boiler substantially as set forth.

6. The combination of the boiler, the receiver connected with said boiler below the water-line in the latter, a steam connection between the boiler and receiver, a float-operated valve controlling such steam connection and arranged for operation by the water in 80 the receiver, the damper, the float in the receiver for operating said damper, the condensing-radiator connected with the receiver, the connecting-pipes and the heating-radiators provided with a feed-valve arranged to open 85 a vent to the atmosphere when it is adjusted to shut off steam from the radiator substantially as set forth.

7. The apparatus herein described comprising the boiler, the receiver, connections between the boiler and receiver, such connections communicating with the boiler below its water-line, a steam connection between the boiler and receiver, a valve controlling such connection, a float for controlling such valve, 95 such float being arranged for operation by the water in the receiver, the damper, a float in the receiver for operating the damper, the heating-radiators provided with feed-valves arranged to open a vent to the atmosphere 100 when adjusted to shut off steam from the radiators, and connecting-pipes substantially as set forth.

8. In an apparatus substantially as described, the combination with the boiler and 105 a receiver above the water-line of the boiler and connected with such boiler below its water-line, of damper devices, a steam connection between the receiver and the boiler and independent floats arranged in the receiver 110 and connected with and adapted to operate the damper devices and the controlling-valve for the steam connection, and the controlling-valve substantially as set forth.

In testimony whereof I have signed my 115 name to this specification in the presence of two subscribing witnesses.

ALBERT P. BROOME.
